Term of patent 14 years

(Cl. D26—14)

FIG. 1

FIG. 2

FIG. 3

FIG. 1 is a perspective view of an antenna dipole ele-
ment or similar article, showing our new design:

FIG. 2 is a top plan view, the bottom being substantial-
ly a mirror image thereof; and

FIG. 3 is an end elevational view thereof, to an en-
larged scale.

The broken line fragmentary showing of an antenna
array is for illustrative purposes only.

We claim:

The ornamental design for an antenna dipole element

or similar article, substantially as shown and described.
